UNITED STATES PATENT OFFICE.

JOHN C. KOFF, OF PITTSBURGH, PENNSYLVANIA, ASSIGNOR TO THE DUFF MANUFACTURING COMPANY, OF PITTSBURGH, PENNSYLVANIA, A CORPORATION OF PENNSYLVANIA.

LIFTING-JACK.

1,321,456.

Specification of Letters Patent. Patented Nov. 11, 1919.

Application filed March 22, 1919. Serial No. 284,318.

To all whom it may concern:

Be it known that I, JOHN C. KOFF, of Pittsburgh, Allegheny county, Pennsylvania, have invented a new and useful Improvement in Lifting-Jacks, of which the following is a full, clear, and exact description, reference being had to the accompanying drawings, forming part of this specification, in which—

10 Figure 1 is a developed vertical section of a lifting jack embodying my invention, the general plane of the section being on the line I—I of Fig. 2;

15 Fig. 2 is a horizontal section on the irregular line II—II of Fig. 1;

Fig. 3 is a perspective view of the clutch barrel and its brake band;

20 Fig. 4 is a detail sectional view showing one of the friction clutch disks and its engagement with its shaft; and

Fig. 5 is a plan view showing one of the coöperating friction clutch disks.

My invention has relation to lifting jacks and more particularly to screw jacks.

25 One of the objects of my invention is to provide a jack of this type having means of simple, novel and effective character, whereby the action of the load on the jack is caused to automatically lock the jack against

30 lowering movement while the load is being held or lifted. A further object is to provide locking means of this character in which the locking action is directly proportional to the load on the jack, so that such

35 action increases as the load increases.

A still further object is to provide novel and effective means in connection with the locking means, whereby the jack may be rapidly raised and lowered, when desired.

40 The nature of my invention will be best understood by reference to the accompanying drawings, in which I have shown the preferred embodiment thereof and which will now be described, it being premised,

45 however, that various changes can be made in the details of construction and general arrangement of the parts, without departing from the spirit and scope of my invention as defined in the appended claims.

50 In these drawings, the numeral 2 designates the base of the jack having an upwardly projecting cylindrical column 3, in

which is secured the internally threaded nut 4. 5 designates the screw of the jack, which extends through the nut 4 and downwardly in the column 3. Surrounding the column 3 is a lifting shell 6, having secured to its upper end the casing 7, in which the operating parts presently to be described are mounted, and which carries at its upper end 60 a lifting plate 8 to receive the load. This plate is provided with ball bearings at 9. Extending through a suitable bearing 10 in the side of the casing is an actuating stub shaft 11, adapted to receive the usual 65 operating lever (not shown). At its inner end, said shaft carries the beveled pinion 12, whose teeth mesh with the horizontal beveled gear 13, which is keyed to the upper portion of the screw 5.

70 As thus far described, the parts are, in general, of well known character and form no part of my present invention except in combination. 14 designates a clutch member having a saw-toothed clutch face on its 75 lower side and which is keyed to the screw 5 to rotate therewith and to move vertically thereon. This clutch member is pressed by springs 15 into engagement with the correspondingly formed clutch face of a second 80 clutch member 16, which is loosely mounted on the screw 5, just above the thread thereof. The clutch member 16 is formed on its periphery with worm teeth 17, which engage the threads of a worm 18, secured to a horizontal shaft 19 mounted in suitable bearings 85 in the casing 7. This shaft 19 is extended through the casing at one end and is provided with a hand crank 20. This shaft 19 is also provided with a multiple disk friction 90 clutch device comprising one set of clutch disks 21, which are engaged with the shaft 19 to rotate therewith, and another set of intercalating disks 22, which are engaged on their peripheries with a barrel 23. This barrel 95 has a cylindrical outer surface which is surrounded by a friction brake band 24, one end of this band being connected to a fixed pin 25, and the other end to a rod 26, whose end is connected to a lever 27, having a cam 100 or eccentric portion 28, which bears against the casing 7. A spring 29 is arranged to act on the rod 26.

The threads on the screw 5 and also the

threads on the worm 18, are of relatively quick pitch, so that said screws will readily rotate under the action of a load on the jack. The operation is as follows:

- 5 The screw and the lifting head or plate 8 can be quickly run up to the load by turning the crank 20 and thereby turning the screw through the action of the worm 18 and worm wheel 16, the clutch faces of the
- 10 members 14 and 16 engaging to cause said members to rotate together and thereby turn the screw. The shaft 11 is then actuated by its lever in the usual manner to further raise the screw and lift the load.
- 15 During the load-lifting operation, it will be readily seen that the clutch member 14 will turn with reference to the clutch member 16, and said members will act as a safety device to prevent the load running down.
- 20 The clutch member 16 is prevented from turning during this action because of the fact that it is engaged with the worm 18, and the action of the load causes an end thrust on the worm shaft 19, which forces
- 25 the disks of the friction clutch into frictional engagement. The extent of the frictional action of this clutch is directly proportional to the load on the screw increasing as the load increases.
- 30 When it is desired to lower the load, the lever 27 is turned from the position shown in Fig. 1 to a position in which the lower portion of its cam or eccentric bears on the casing. This permits an endwise movement
- 35 of the rod 26 and releases the brake band 24. The barrel 23 is now free to turn, and the entire friction clutch device including said barrel now turns with the shaft 19. This releases the resistance acting on the
- 40 clutch member 16, and the lowering action can then be controlled by manipulation of the lever 27. Also, the friction clutch device may be left in and the lowering controlled by the crank 20. In this manner,
- 45 the jacks can be lowered to any desired extent and stopped in the desired position.

The advantages of my invention will be apparent to those familiar with jacks of this type, since it provides a high-speed jack capable of handling large loads with perfect safety, the locking action against accidental lowering of the load increasing as the load increases. At the same time, the invention provides means whereby the load may be quickly lowered to any desired extent whenever necessary.

The method of construction and mode of operation is simple, and the parts thereof are strong and of durable character.

60 I claim:

1. A lifting jack having a lifting screw, two independent sets of mechanisms connected to the screw whereby it may be raised and lowered, one of said sets of mechanisms

including an automatic clutch to prevent the screw from rotating in one direction and to permit free rotation of the screw in the other direction by the other mechanism, said clutch being mounted on the shaft of the screw, and another clutch device for controlling the operation of the first named clutch, substantially as described.

2. A lifting jack having a lifting screw, means for actuating said screw to raise the load, a two-part clutch, one member of which is mounted to rotate with the screw and the other member of which is loosely mounted with respect to the screw, a quick pitch worm geared to the first named clutch member and having an endwise movable shaft, manually operated actuating means for said shaft, a brake device applied to said shaft, and manually operated means for controlling said brake device; substantially as described.

3. A lifting jack comprising a lifting screw, means for actuating said screw to raise the load, a clutch device having one member fixed to rotate with the screw and another member mounted loosely with respect to the screw, said last named member having worm teeth thereon, a worm shaft, a worm on said shaft engaging said teeth, means for manually operating said shaft, and a friction brake device comprising friction elements carried by said shaft, and other coöperating friction elements carried independently of the shaft, and manually controlled means for effecting the engagement and disengagement of the two sets of friction braking elements; substantially as described.

4. A lifting jack having a lifting screw, means for actuating said screw to raise the load, a clutch having one member mounted for rotation with the screw and another member loosely mounted with respect to the screw, the last named member having worm teeth on its periphery, a worm shaft, a crank for actuating said shaft, a worm on said shaft and engaging said worm teeth, a barrel or casing surrounding said shaft, a set of friction members carried by the barrel or casing, a coöperating set of friction members carried by said shaft, and means whereby the barrel or casing may be held against movement or may be free to turn with the worm shaft, substantially as described.

5. A lifting jack having a lifting screw, means for actuating said screw to raise the load, a clutch having one member mounted for rotation with the screw and another member loosely mounted with respect to the screw, the last named member having worm teeth on its periphery, a worm shaft, a crank for actuating said shaft, a worm on said shaft and engaging said worm teeth,

a barrel or casing surrounding said shaft, a set of friction members carried by the barrel or casing, another set of friction members carried by the shaft, and means whereby the barrel or casing may be held against movement or may be freed to turn with the worm shaft, said means compris-

ing a brake band engaging the barrel or casing and a handle device for applying and releasing the brake band, substantially 10 as described.

In testimony whereof, I have hereunto set my hand.

JOHN C. KOPF.
